UNITED STATES PATENT OFFICE.

WARREN JAMES GRONINGER, OF PORT ROYAL, PENNSYLVANIA.

VALVE FOR INTERNAL-COMBUSTION ENGINES.

1,247,824.

Specification of Letters Patent. Patented Nov. 27, 1917.

Application filed July 13, 1917. Serial No. 180,407.

To all whom it may concern:

Be it known that I, WARREN JAMES GRONINGER, a citizen of the United States, residing at Port Royal, in the county of Juniata 5 and State of Pennsylvania, have invented a new and useful Valve for Internal-Combustion Engines, of which the following is a specification.

The device forming the subject matter of 10 this application is an internal combustion engine, and one object of the invention is to provide novel means whereby the valves of the engine may be taken apart readily, to facilitate cleaning or repair, and to give access to the space between the cylinder head 15 and the piston.

Another object of the invention is to provide an engine of the type above mentioned, having valves with which there will be no 20 trouble caused by carbon deposits on the valves, a condition frequently arising when beveled valves fit on a beveled seat.

Another object of the invention is to improve the valve construction by reducing to 25 the greatest possible extent, the wear on the valves.

It is within the province of the disclosure to improve generally and to enhance the utility of devices of that type to which the present 30 invention appertains.

With the above and other objects in view which will appear as the description proceeds, the invention resides in the combination and arrangement of parts and in the 35 details of construction hereinafter described and claimed, it being understood that changes in the precise embodiment of the invention herein disclosed can be made within the scope of what is claimed, without departing from the spirit of the invention.

In the accompanying drawings:—

Figure 1 shows in side elevation, an internal combustion engine constructed in accordance with the present invention, parts 45 appearing in section;

Fig. 2 is a section taken approximately on the line 2—2 of Fig. 1;

Fig. 3 is a top plan of the engine, parts being broken away;

Fig. 4 is a composite perspective wherein 50 portions of the valve mechanism are shown in spaced relation.

The numeral 1 denotes the crank case of an internal combustion engine, carrying any 55 desired number of cylinders 2. The crank shaft is shown at 3 and the cam shaft ap-

pears at 4, the latter carrying cams 5. The crank shaft 3 is connected with pitmen 6 carrying pistons 7 working in the cylinders 2. Spark plugs 8, mounted in the heads of 60 the cylinders 2, or any other suitable ignition mechanisms, are provided. The foregoing are common engine details which may be passed over briefly.

The cylinders 2 are provided at one side 65 with a horizontal shoulder 9 and above the shoulder 9, the cylinders 2 are supplied with lateral openings 10 communicating with the space between the pistons 7 and the heads of the cylinders. Supported on the shoulder 9 and abutting against the side of the cylinders is a gasket 11 having ports 12 communicating with the openings 10 in the cylinders 2. Supported on the shoulder 9 and abutting against the gasket 11 is a carrier or block 14, held in place by bolts 15 or other securing elements, engaging the carrier or block and engaging the cylinders 2. If desired, a cover plate 16 may be secured detachably to the block or carrier 14 70 and to the upper portion of the crank case 1, for the purpose of housing and protecting certain of the movable parts of the device. The cover plate 16 is a useful but not mandatory element.

85 The carrier 14 is provided with bores 17 the axes of which are parallel to the axes of the cylinders 2. The carrier 14 includes a base 18. The carrier 14 is supplied with inner ports 19 coinciding with the ports 12 80 of the gasket 11 and communicating with the cylinders 2 by way of the lateral openings 10 in the cylinders. The carrier 14 is provided with outer ports 20 disposed diametrically opposite to the ports 19.

95 A sleeve 22 of cylindrical form is disposed in each bore 17 and is supported on the base 18 of the carrier 14. The sleeve 23 has an inner port 24 coinciding with one of the ports 19 in the carrier 14, and has, 100 also, an outer port 24 coinciding with one of the ports 20 of the carrier 14. The ports 23 and 24 in the sleeve 22 are disposed diametrically opposite to each other. The sleeve 22 is held in the bore 17 by means of a cap 25, of cup-shape, the cap 25 being threaded into the upper end of the bore 17. If desired, as indicated in Fig. 3, the inner surface of the wall of the cap 25 may be fluted at 26, to facilitate a rotation of the 110 cap. The cap 25 bears on the upper end of the sleeve 22 and binds the same on the base

18 of the carrier 14. The cap 25 may carry an oil cup 27.

Mounted to reciprocate in each sleeve 22 is a valve 28 of the piston type, the same having right line movement in the sleeve. The valve 28 may have a reduced passage 29 therethrough, to prevent compression between the valve and the cap 25. The valve 28 is assembled with a stem 30 mounted to slide in the base 18 of the carrier 14. The lower end of the stem 30 is removably seated in the socket 31 formed in the upper end of a plunger 32 mounted to reciprocate in the top portion of the crank case 1, or otherwise supported. At its lower end, the plunger 32 is provided with a head 33 coating with one of the cams 5 on the cam shaft 4. Each valve stem 30 carries an abutment 34 held in place by a pin 35 or otherwise. A compression spring 36 surrounds a portion of each stem 30, the lower end of the spring engaging the abutment 34, and the upper end of the spring engaging the base 18 of the carrier 14.

Each of the cylinders 2 is provided with two valve structures of the sort above mentioned. Preferably, noting Fig. 1, the valves of the innermost stems 30 are intake valves, the valves of the outermost stems being exhaust valves. The novelty, however, resides in the specific valve construction, whether or not the same be duplicated, and whether or not the construction relates to an intake valve or an exhaust valve.

The operation of the valves 28 is simple. When the cam shaft 4 is rotated, the cam 5 raises and lowers the plunger 32 and the latter raises and lowers the stem 30. When the stem 30 is raised, the spring 36 will be put under compression, and the stem 30 will move downwardly under the action of the spring 36.

When the valve 28 is seated on the base 18 of the carrier 14, the ports 23 and 24 will be closed by the valve, and the passage of the fuel or the exhaust will be cut off. When, however, the valve 28 is raised, as shown in Fig. 2, then communication is established with the bore of the cylinder 2 between the piston 7 and the head of the cylinder.

Especial attention is directed to the fact that as the valves 28 reciprocate, the carbon or other deposits thereon will tend to be scraped off by contact with the edges of the

ports 24 and 23 in the sleeve 22. The valve, therefore, to a large degree, is self-cleaning.

One of the important features of the invention arises out of the ease with which access may be had to the valves 28 and the sleeves 22. In order to remove one of the sleeves 22, it is necessary merely to take out the cap 25. Ordinarily, the bolts 15 are removed, and the block or carrier 14 is lifted off the shoulder 9, carrying with it the sleeves 22, the valves 28 and the stems 30. In this way, access is had to the space in the cylinders 2 above the pistons 7 and any of the valves 22 may be taken out of the block or carrier 14, readily, by moving the cap 25. The valves 22 are lubricated by means of the oil cups 27. It is to be observed that carbon deposits on the valves 28 will be scraped off to a large extent, as the valves reciprocate, and since the valves are not of the common bevel-edge type, carbon deposits cannot accumulate between the valves and their seats, thereby preventing a proper closing of the valves.

Having thus described the invention, what is claimed is:

An internal combustion engine comprising a cylinder having a lateral shoulder; a carrier having a bore and a single pair of oppositely disposed ports located at the same elevation, one of which ports opens into the cylinder, the other of which ports opens directly through the outer wall of the carrier, the carrier being supported on the shoulder; means for securing the carrier detachably to the cylinder; a sleeve of common diameter from end to end seated in the bore and having ports coinciding with the ports of the carrier; a solid disk-like valve mounted to reciprocate in the sleeve and of sufficient thickness to close the ports, the valve having a minute opening therethrough; a closure threaded into the carrier and engaging the sleeve to hold the same in the bore; and a lubricating means mounted directly on the closure and discharging into the sleeve, the closure being imperforate about the lubricating means.

In testimony that I claim the foregoing as my own, I have hereto affixed my signature in the presence of two witnesses.

WARREN JAMES GEONINGER.
